UNITED STATES PATENT OFFICE.

JOHN M. REYNOLDS, OF CHICAGO, ILLINOIS.

SHELL ORNAMENT.

SPECIFICATION forming part of Letters Patent No. 291,401, dated January 1, 1884.

Application filed October 3, 1882. (Model.)

To all whom it may concern:

Be it known that I, JOHN M. REYNOLDS, a citizen of the United States, residing in Chicago, county of Cook, and State of Illinois, have invented certain new and useful Improvements in Shell Ornaments, of which the following is a specification.

This invention relates to improvements in shells for ornamental purposes, which shells belong to the species technically known as the *Strombus* or those which are spiral and have an external border or lip dilated into a wing, but more particularly described in its application to what is commonly known as the "conch-shell."

The object of the invention is to provide a shell ornament adapted to be used as a vase, an ornamental hook, or a suspended basket for the reception of flowers, vines, &c., the outside of which shall show only the naturally highly-polished and beautifully-tinted surface of the shell, to the exclusion of the rougher and irregular parts, which would unfit the shell for these purposes; and also to provide the shell ornaments above referred to with a base or opening to adapt it for such purposes. I attain this object in the manner illustrated in the accompanying drawings, in which—

30 Figure 1 is a perspective of a conch-shell in the condition ordinarily sold upon the market, and Fig. 2 a side elevation of that portion of the same embodying my invention.

It is well known that the beauties of a conch-shell consist, principally, if not wholly, of the naturally highly-polished and beautifully-tinted inner surface of the shell, and that the value of the shell in the market is dependent upon the extent of the projection of the lip, and corresponding exposure of this inner surface of the shell. The size of the shell also affects its value if the extent of the exposure and tint of its inner surface corresponds in area and brilliancy; but conch-shells of the larger size are by reason of their proportions unfitted for mantel or wall ornaments, which unfitness is increased by the somewhat unsightly appearance of the rough and irregular outer surface; hence such shells 45 are usually employed to ornament the hearth of fire-places, or else placed on the floor in the corners of rooms. It is also well known among those accustomed to handling such shells that their interior polished and tinted

surfaces form a symmetrical spiral, and that 55 the tints of this spiral (not exposed in the shell in its ordinary state) are deeper as they approach the inner part of the spiral—or, in other words, the most beautiful parts of the shell in its natural state are hidden from 60 view. By my invention I propose to utilize alone this interior portion of the shell for vases or ornamental hooks or hanging-baskets by cutting or sawing away the rough exterior of the shell on the line *a b*, Fig. 1, 65 leaving only the spiral highly polished and tinted interior, which, when separated from the rougher part, has the general appearance of a cornucopia formed by wrapping a piece of paper about itself, except at the point of this 70 interior of the shell which is somewhat hook-shaped in its natural condition, as shown in Fig. 2. It is obvious, however, that in order to have the ornament so formed provided with only the natural polished and tinted surface, and in condition to stand on end for a vase, as shown in Fig. 2, or to receive flowers when used as a hanging-basket, the cone 75 end of the shell must be removed; hence I saw or cut the shell through on the line *b c*, as 80 shown in Fig. 2.

Cutting the shell in the above-described manner to expose its beautiful surface only and adapt it to the purposes referred to greatly increases its value, as has been repeatedly and 85 practically demonstrated, and, furthermore, the shell is adapted to useful purposes, which cannot be attained when in its natural state.

In addition to the increased value of the shell when converted into the ornaments 90 above described, it may be added that in some species of the *Strombus* the part removed is of considerable value for and is utilized in making shell jewelry, paper-weights, and other small articles for ornamental and practical purposes. 95

Having thus described my invention, what I claim, and desire to secure by Letters Patent, is—

A shell ornament consisting of the spiral 100 naturally polished and tinted interior only of the *Strombus* species of shells, substantially as described.

JOHN M. REYNOLDS.
